UNITED STATES PATENT OFFICE.

CHARLES W. NOKES, OF CLEVELAND, OHIO, ASSIGNOR OF ONE-HALF TO
EDWIN A. BONFIELD, OF SAVANNAH, GEORGIA.

DESIGN FOR A GAS-BURNER TIP.

SPECIFICATION forming part of Design No. 33,220, dated September 18, 1900.

Application filed June 9, 1900. Serial No. 19,779. Term of patent 7 years.

To all whom it may concern:

Be it known that I, CHARLES W. NOKES, a citizen of the United States, residing at Cleveland, in the county of Cuyahoga and State of Ohio, have invented and produced a new and original Design for Gas-Burner Tips, of which the following is a specification, reference being had to the accompanying drawings, forming part thereof.

10 In the accompanying drawings, forming part of this specification, Figure 1 is a plan view of my new design in gas-burner tips. Fig. 2 is a full side elevation thereof, and Fig. 3 is an edge elevation.

15 As thus shown, the leading or material feature of my design consists in its configuration or appearance as a whole, and especially of its head 6, which is its chief embodiment, having flat sides 7 opposite inward inclines 20 carrying the opposed and peculiar burner-points 2, mounted on said inclines, as shown. These points are each formed with two clearly-

marked diameters of about equal depth, the lower diameter having lateral openings 3 clearly visible outside, and a bore 4 extends centrally into said points from the top and is likewise plainly visible to the eye. These points 2 stand at right angles to each other; and a semicircular depression 5 relieves the space between them at the bottom of the two 25 inward inclines on the head 6. The bottom of said head is itself relieved by a hollow tubular extension bearing the proportions to said head relatively as shown.

What I claim is—

35 The design for a gas-burner tip, substantially as shown and described.

Witness my hand to the foregoing specification this 18th day of May, 1900.

CHARLES W. NOKES.

Witnesses:

H. E. MUDRA,
R. B. MOSER.
